No. 784,098.

PATENTED MAR. 7, 1905.

W. S. BEAZLEY.
DENTAL ROOT EXTRACTOR.
APPLICATION FILED JUNE 18, 1904.

UNITED STATES PATENT OFFICE.

WALTER S. BEAZLEY, OF LANCASTER, KENTUCKY.

DENTAL ROOT-EXTRACTOR.

SPECIFICATION forming part of Letters Patent No. 784,098, dated March 7, 1905.

Application filed June 18, 1904. Serial No. 213,169.

To all whom it may concern:

Be it known that I, WALTER S. BEAZLEY, a citizen of the United States, residing at Lancaster, in the county of Garrard and State of Kentucky, have invented a new and useful Improvement in Dental Root-Extractors, of which the following is a specification.

This invention relates generally to dental instruments, and more particularly to one for extracting the roots of broken teeth without the use of forceps or the laceration of the surrounding tissues; and with this object in view my invention consists, essentially, in the employment of one tube sliding within another, the inner tube being provided with legs having padded feet which rest upon the adjacent teeth, the outer tube having a bar connected thereto which slides in the inner tube, said bar carrying a hooked rod which is adapted to engage the eye of a screw which is screwed into the root to be extracted, the inner and outer tubes being provided with handles which are adapted to be brought together for the purpose of drawing the hooked rod up into the inner tube, thereby extracting the root.

The invention consists also in certain details of construction hereinafter fully described, and pointed out in the claims.

In the drawings forming a part of this specification, Figure 1 is a perspective view of an instrument constructed in accordance with my invention. Fig. 2 is a side view of the same in process of operation. Fig. 3 is a vertical sectional view. Fig. 4 is a detail sectional view taken through the lower end of one of the legs and showing the rubber foot or pad arranged in the shoe.

In carrying out my invention I employ a tube A, which may be of any desirable material and which has a handle B connected to the upper end thereof by means of a bolt B', passing through the handle B into a plug B'', fitted tightly in the upper end of the tube A. The lower end of the tube A is enlarged or formed with a collar A', and from which extend the legs C, which diverge slightly at their lower ends and are provided with cup-shaped shoes or sockets D, in which the rubber pads E are inserted, said rubber pads or feet being a sufficient distance apart to strad-

dle the root which is to be extracted and bear upon the next adjacent teeth, as most clearly shown in Fig. 2.

F indicates a tube sliding upon the tube A, and connected to this tube F is a round bar G, 55 which slides within the tube A, said bar G and tube F being connected by means of a bolt H, which passes through the tube F and bar G and works in the longitudinal slots I, produced in the tube A, and a coil-spring K is 60 arranged within the tube A and bears at its upper end upon the plug B'' and at its lower end upon the bar G, the purpose of said spring being to normally throw the bar G and tube F downwardly to the positions indicated in 65 Figs. 2 and 3.

L indicates laterally-projecting handles attached to the tube F and by means of which said tube is caused to move upwardly upon the tube A, the handle B being held in the 70 palm of the hand while the index and middle fingers are brought into engagement with the handles L, and by pulling upwardly upon said handles the outer tube and the bar G, connected therewith, are caused to move upwardly 75 or toward the handle B.

A rod M is rigidly connected to the lower end of the bar G, the lower end of said rod terminating in a hook M', which is adapted to engage the eye N' of the bolt N, which is 80 screwed into the root to be extracted, as most clearly shown in Fig. 2. After the hook has been made to engage the eye a gradual pull or pressure is exerted upon the handles L, as before stated, and the root can be quickly and 85 easily extracted without the use of forceps or without the laceration of the surrounding tissues, as it is obvious that there will be a straight and direct pull upon the root and that the bearing or pressure will be exerted entirely 90 upon the next adjacent teeth.

Having thus fully described my invention, what I claim as new, and desire to secure by Letters Patent, is—

1. A dental instrument of the kind described 95 comprising an inner and outer tube, both provided with handles, the inner tube having a bearing-support at its lower end, the outer tube carrying a bar terminating in a hook at the lower end, said hook being adapted to en- 100

gage a screw-eye, and means for returning the said parts to their normal positions.

2. A dental instrument of the kind described comprising an inner tube having a handle at its upper end and supporting-legs at its lower ends, said legs being provided with cushioned feet, an outer tube provided also with handles and having a bar connected thereto, said bar sliding within the inner tube and carrying a rod which terminates in a hook said hook being adapted to engage a screw-eye, and the spring for returning said parts to their normal positions.

3. A dental instrument of the kind described comprising an inner tube having a handle at the upper end and the legs at the lower end, said

legs being provided with cushioned feet, an outer tube provided with laterally-projecting handles, a bar movable in the inner tube and connected to the outer tube by means of a bolt, ²⁰ said bolt working in the longitudinal slots produced in the inner tube, a spring arranged within the inner tube and adapted to bear upon the upper end of said bar, a rod carried by the bar and terminating in a hook at its lower ends ²⁵ and a screw-eye adapted to be engaged by said hook for the purpose specified.

WALTER S. BEAZLEY.
